United States Patent Office.

EUGÈNE BOURDON, OF PARIS, FRANCE.

Letters Patent No. 70,511, dated November 5, 1867.

IMPROVED DEVICE FOR OPERATING FOLDING VALVES.

The Schedule referred to in these Letters Patent and making part of the same.

TO ALL WHOM IT MAY CONCERN:

Be it known that I, EUGÈNE BOURDON, Engineer, of 36 Rue de Malte, Paris, in the Empire of France, have invented "Improvements in Valves for Regulating the Flow of Liquids, Gases, and other Elastic Fluids;" and I do hereby declare that the following is a full and exact description thereof, reference being had to the accompanying sheet of drawing, and to the figures and letters of reference marked thereon.

In pipes used for conveying water, gases, or other elastic fluids, there are cocks, and clack and other valves for regulating their distribution, and, when the pressure of the fluid is very great, considerable power is required to open and to close these cocks and valves.

To overcome this difficulty I have invented a flexible valve, which opens easily, with very little force. This valve is nothing but a membrane, that is to say, a strip or band of supple material, fitting exactly on the edges of the openings by which the water or the gases are to issue, in order to close the said openings. This strip or band is attached to the end of a lever, which unrolls it in applying it on the orifice which is to be closed, or winds it up in lifting it when the orifice is to be opened. I make these valves of thin skin, of leather, of India rubber, of gutta percha, or other analogous material, according to the nature of the fluid which is to be retained, and also according to the dimensions which I must give to them. In every case these flexible valves must be of a material impervious to the fluid which is to be retained, and not to be attacked thereby. Thus, for water or air, I make my valves of leather, of India rubber, of a woven fabric prepared with India rubber, or of gutta percha. For illuminating gas, I can make them of greasy leather, of cloth, or felt impregnated with a fatty matter, of sulphurized India rubber, or analogous material. For steam, I make them of wire gauze, lined or coated with some soft and elastic material which will fill its meshes. I might also use an assemblage of small copper plates, brought edge to edge by hinges, which would give them the pliability requisite for the winding up and unwinding of the valve; or I can use certain combinations of metallic plates and wires which have almost as much flexibility as membranes.

It will be observed that one of the great advantages of these flexible valves is that they close hermetically, by fitting exactly on the edges of the openings, without any previous dressing or grinding of the surfaces in contact, which saves labor both in fitting these valves and in keeping them in repair.

To enable others skilled in the art to understand and use my invention, I will now proceed to describe the manner in which the same is or may be carried into effect by reference to the accompanying drawings.

Figures 1 and 2 are two sections of one of these valves in its box, the first following the line A B, and the second the line C D.

M is the valve-box or chamber. It may be closed in front by a sheet of glass, I, which will permit inspection of the working of the valve.

The water enters by the elbow pipe P, and issues through the orifice R, which is composed of a number of small holes, m m m, pierced in the plate T or bottom of the box. All these openings m m m are closed by the flexible valve Q, which is a strip of leather fitting exactly on the plate T.

It will be evident that if the outlet R were a single opening, the valve, not finding sufficient support, would sink into this opening, and would soon be destroyed.

The valve Q is attached at one end to the extremity of a lever-arm, L, and at the other to the plate T.

The lever L is joined to the axle K K', which passes out of the box, traversing with gentle friction the screw-jacket J, and the conical part x forms a hermetical joint. A handle, which is fixed on the end K' of this axle, serves to give it motion, that is to say, to open and close the valve Q. When the lever is in the position indicated by L, the valve is stretched and the orifice R closed; but when this lever is brought from L to L', it lifts the valve, which winds in the direction of Q', and then the orifice R or the passages m m m open almost without effort.

The figs. 3 and 4 show another arrangement of flexible valve, the same letters indicating the same parts as in the preceding figures.

Figure 3 is a front view of the box, with its valve, and

Figure 4 is a section of it at X X.

M is the box, closed in front by the sheet of glass I; P-the inlet and R the outlet pipe.

T is a cylindrical concave plate, adjusted at the bottom of the box, and pierced with holes *m m m*, for the exit of the fluid by the elbow pipe R.

Q is the flexible valve, say of leather, attached at one end to the lever L and at the other to the plate T. This valve is opened and closed by means of the handle *f*, fixed on the end K' of the axle of the lever L.

The Figures 5 and 6 are a front and a sectional view at *y y* of another flexible-valve box, which may be used advantageously in place of what is termed a two-way cock.

P is the inlet pipe, and there are two outlet pipes, R and R', separated by a partition, A, which runs between the bottom of the box and the plate T.

The valve Q Q' is double, and is shown in the position in which it closes the two orifices. If the lever L is turned to the right it opens the orifice R, and if it is turned to the left it opens R'. This arrangement of valve bears a great analogy to the slide-valves of steam engines, and might replace them very advantageously, which I reserve the right of doing. The steam would arrive by the pipe P, and enter the cylinder at one end by the orifice R, and at the other end by the orifice R'. In this case the box M would be a steam-chest.

Figure 7 is the front view of a flexible-valve box, the plate T of which is a cylindrical surface, slightly convex, the effect being that the valve, when placed in the position shown on the drawing at Q, finds itself tightly stretched on the plate T, which is a condition required for the perfect closing of the orifice. When the lever comes from L to L' the valve is entirely raised.

Figure 8 is a front view of the same box, with flexible valve, but the valve is connected with the lever L in another way. It is, however, still drawn and stretched on the convex plate T, but drawn more directly.

What I claim as my invention, and desire to secure by Letters Patent, is—

The combination with the valve-box, and suitable orifice or orifices formed therein, of the membranous or flexible valve, and lever for operating the same, substantially as and for the purposes herein set forth.

E. BOURDON.
